United States Patent

Des. 240,086
Patented May 25, 1976

240,086

SPRAY SHIELD

Edward L. Riblett, Winter Park, Fla. (414 Piedmont St., Orlando, Fla. 32806), and John J. Davis, 2580 S. Orange Blossom Trail, Orlando, Fla. 32805

Filed Apr. 19, 1974, Ser. No. 462,214

Term of patent 14 years

Int. Cl. D28—03

U.S. Cl. D86—10 A

Fig. 1.

Fig. 2.

Fig. 3.

FIG. 1 is a perspective view of a spray shield showing our new design;

FIG. 2 is a right side elevational view; and

FIG. 3 is a rear elevational view.

I claim:

The ornamental design for a spray shield, substantially as shown and described.
